 In Germany February 13, 1934

6 Claims. (Cl. 179—18)

In telephone systems with automatic operation the establishment of a connection with a free line of a group of lines leading in the same direction is generally effected by a selector located in the speaking route so arranged that it automatically selects a free line from an outgoing group of lines leading in the desired direction, for example to another exchange. Since, except for comparatively rare exceptions, the lines are numbered consecutively, they are also connected consecutively to the sets of contacts in the banks of the selector, particularly the final selector. Difficulties of operation arise, however, if number of outgoing lines in a particular direction, for instance the lines leading to one private branch subscriber, have to be increased or reduced. For commercial reasons, it is only possible in the most isolated cases to give the subscriber a new call number when altering the number of his lines. On the other hand it is also undesirable to connect up the newly required lines to another group of switches, since then when the number is called and is found to be busy the completion of the connection to a free line, which is reached over quite another group of lines, can only be carried out by the provisions of auxiliary devices which seriously complicate the whole installation. It has therefore been proposed, to enable an increase in the number of lines to be made, to cut the bank multiple, which however, has the disadvantage that there is then no longer any through multiple field, and with this arrangement if the number of lines is to be reduced it is necessary to connect up the multiple again in order to permit the calling subscriber to have access to all the lines of the group.

In order to permit the multiple capacity of an exchange having a given number of selecting stages, to be utilized as fully as possible when it includes a large number of line groups extending in different directions, it has also been proposed to reach these line groups over parallel or succeeding switches. With known arrangements of this kind, however, the multiple field of the switch, for instance the final selector, by the setting of which a calling party obtains connection with the desired line group, cannot be connected straight through but for each group of outgoing lines a single non-multiplied contact must be provided in each impulse receiver over which either a succeeding selector associated with the impulse receiver is reached or a characterizing relay is operated by means of which the connection can be set up with a free line of a desired group over a parallel switch. If only a single group of lines

can be reached over the parallel switch it will naturally follow that this switch can be started up to select a free line without the intermediate connection of a special group characterizing relay. These arrangements also possess the disadvantage that the multiple field needs to be altered when an individual subscriber becomes a P. B. X. subscriber or vice versa.

The object of the present invention is to produce an arrangement which ensures that in one instance the multiple capacity given by the number of numerical selecting switches is utilized as far as possible, and in the other instance the selectors at the switching stages over which the various groups of lines leading in the same direction are reached, may have a straightforward multiply connected contact field so that in the event of an alteration, particularly an increase in the number of lines extending in the various traffic directions (P. B. X. lines), operations on the straight forward multiple field shall be avoided, and particularly the cutting of the multiple and the connecting up of non-multiplied individual characterizing lines to the various positions in the contact field. This is accomplished by the employment of a multiply connecting characterizing line associated with a group of lines leading in the same direction, together with a call allotter arranged so that after the seizure of the characterizing line which is accessible over all the speaking route switches of the group and is therefore multiply connected, a connecting path is set up under the control of a call allotter which is common to the group of speaking route switches with a free line of a desired group of an auxiliary switch, for example, a succeeding switch or a parallel switch, associated with the speaking route switch which has been used. If succeeding switches are employed, preferably a succeeding switch or a set of succeeding switches is accessible over a non-multiplied contact of the speaking route switch which is located beyond the contact groups. In the case of switches with motion in a plurality of directions (vertical and rotary switches) this succeeding switch or set of succeeding switches is preferably reached over a contact located at the end of each level. It is not necessary that the switching contact for the succeeding switches should actually be the last in the contact bank as this is generally used for other purposes, for instance statistical purposes.

Figs. 1-3 show embodiments of the invention.

Fig. 1 shows in principle the arrangement according to the invention applied to an installation with succeeding switches;

Fig. 2 shows the arrangement with parallel switches;

Fig. 3 is an embodiment including all the details.

5 When the final selector LW1 in Fig. 1 is set on to the characterizing line after it has been seized, which line is associated with a group of lines leading in the same direction and is accessible over all the speaking route switches, a connecting path is set up with a free line of the desired group under the control of the allotter VO over a succeeding switch NW1 associated with the final selector LW1 which has been employed. After the setting of the final selector LW1 on 10 the characterizing line which marks the group of P. B. X. lines MA1, the allotter VO is set into engagement with the final selector LW1. The marking of the lines MA1 is effected by the relay BZ1 energized over the characterizing line so 15 that the succeeding switch NW1 sets itself on to a free one of the lines MA1. After this setting the allotter VO initiates a further movement of the final selector LW1 to an overflow position over which the succeeding switch NW1 is accessible. It is quite immaterial for the purpose of 20 the invention how the final selector LW1 is constructed and the particular position of the final selector over which the succeeding switch NW1 is reached. The final selector LW1 is shown as a 25 rotary switch with a plurality of contact groups which rotates until it reaches the overflow position over which the succeeding switch NW1 is accessible.

The final selector LW2 in Fig. 1 is also a rotary switch with a plurality of groups of contacts but in this case the succeeding switch NW2 is connected to normal contacts provided between the individual groups so that after the succeeding switch NW2 has been set on to a free line 30 in the desired P. B. X. group, the final selector LW2 has only to move to the next normal position to which the succeeding switch NW2 is connected.

The final selector LW3 in Fig. 1 is a vertical 35 and rotary switch and in this case the succeeding switch is reached over the multiply-connected overflow contacts of the individual levels.

The individual P. B. X. line groups are connected to the succeeding switch LW1 accessible 40 over the final selector NW1 and to the succeeding switch LW2 over the final selector NW2 of the individual lines and can be connected up as desired either successively or interspersed. The 45 succeeding switch NW3 which is reached over the final selector LW3 is divided into three individual switches over each of which a group of P. B. X. lines is accessible.

In accordance with Fig. 2 after the setting of 50 the final selector LW1 on to the multiply connected characterizing line and the energization of the marking relay of the desired group of P. B. X. lines, an allotter VO is likewise set on to the final selector in use. The group of P. B. X. lines on to which the parallel switch, e. g., the 55 switch PW1, is to be set is marked by the marking relay. After the setting of the parallel switch on to a free line of the desired group, the connection is completed between the parallel switch and the connecting path to the final selector.

70 Fig. 3 shows an arrangement in full detail. After the setting of the final selector LW1, which is in the form of a vertical and rotary switch, on to the multiply-connected characterizing lines 75 1, 2, and 3, the allotter VO is set on to the final

selector LW1. The marking relay BZ3 is operated over the characterizing line 2 and marks the group of P. B. X. lines to which the lines SA31 and SA32 belong; thereupon the succeeding switch NW sets itself on to a free line of the 5 P. B. X. group whereupon over wiper a of the allotter VO a starting circuit is completed for setting the final selector LW on to the overflow contact 11.

If a calling subscriber desires a connection 10 with the group of P. B. X. lines SA3 (lines SA31, SA32), the seizing relay C is energized from a preceding selector on the seizure of the final selector LW1. In order to set the final selector LW1 to the required level the relay A is energized 15 by impulses sent by the preceding switch and operates the vertical magnet, (not shown), in the usual manner. The off normal contacts of the switch are operated on the first vertical step and contact 2k is closed. During the operation 20 of the vertical magnet, (not shown), relay V is energized and releases at the end of the impulse series. The following circuit is then completed for relay U: earth, contacts 2k, 3v, 4c, shaft contact 5w, winding I of relay U, battery, earth. 25

Relay U prepares a circuit for the rotary magnet DLW1 of the final selector LW1 by closing the contact 6u. In response to the further impulses sent out by the subscriber, relay A is again energized and the rotary magnet DLW1 is operated 30 over: earth, contact 7a, relay V, contacts 6u, 8p, rotary magnet DLW1, battery, earth. By means of the rotary magnet DLW1 the final selector 35 LW1 is set on to the desired contact over which the multiply connected characterizing lines 1, 2, and 3 are accessible. During the operation of the rotary magnet DLW1 relay V is energized. As soon as the final selector LW1 takes its first step, the shaft contact 5w is opened and hence the 40 energizing circuit over winding I of the relay U is interrupted. Relay U, however, remains energized during the impulse series over: earth, contacts 10c, 11v, 12u, winding II of relay U, battery, earth. After the setting of the final selector 45 LW1 has been completed relays U and V are released, first the relay V and shortly afterwards the relay U owing to the opening of contact 11v. With relay V deenergized and relay U still energized the following test circuit is completed: 50 earth, contacts 13c, 14v, 15u, windings I and II of relay P, lead 15, relay G, wiper f of the succeeding switch NW in position O, lead 16, wiper c of the final selector LW1 on line 3, lead 17, resistance W3, relay An, battery, earth.

55 Relay P operates in this circuit and opens contact 18p and closes contact 19p. Thereupon the following blocking circuit is completed: earth, contacts 13c, 19p, winding II of relay P, lead 15, relay G, wiper f of the succeeding switch NW in the normal position, lead 16, wiper c of final 60 selector LW1 on line 3, lead 17, resistance W3, relay An, battery, earth. With these circuit conditions seizure of the multiply connected characterizing lines 1, 2, and 3 by another final selector is prevented. Relay P closes contacts 20p and 65 21p thereby effecting switching through in the final selector LW1. Relay G also operates in the circuit over wiper c of the final selector LW1 and by closing contact 22g prepares the test circuit 70 for the allotter VO. Relay G also by closing 23g prepares a circuit over wiper b of the allotter VO.

75 Relay An also operates in a circuit over wiper c of the final selector LW1 and at contact 24an completes the following circuit for the driving 75

magnet DO of the allotter VO; earth, contacts 24an, 25po, driving magnet DO of the allotter VO, relay interrupter RU2, battery, earth. By means of the relay interrupter RU2 impulses are transmitted to the rotary magnet DO and the allotter VO is advanced until the following circuit, which was prepared at contact 22g, is completed over wiper d of the allotter VO, earth, battery, relay PO, wiper d of the allotter VO, contact 10 22g, relay PV, earth. Relays PO and PV are energized in this circuit. Relay PO opens contact 25po which interrupts the circuit of the rotary magnet DO. The following circuit is now completed over wiper b of the allotter VO; earth, battery, resistance W5, contact 26po, wiper b of the allotter VO, contacts 23g, 21p, wiper b of the final selector LW1, lead 2, winding I of relay BZ3, earth. Relay Y is connected in parallel with winding I of relay BZ3. Relay Y, however, cannot operate since relay BZ3 is of low resistance compared with relay Y. Relay BZ3 serves to mark the P. B. X. lines connected to the succeeding switch NW. In the present case only two lines are shown, namely SA31, SA32, which are connected to contacts 2 and 4 of the succeeding switch NW. The marking of these lines is effected by the closing of contacts 27b23 and 28b23.

After the setting of the allotter VO the following circuit is completed over wiper c of the allotter VO; earth, relay interrupter RU1, contact 29po, wiper c of the allotter VO, contact 30pnw, relay UNW, rotary magnet DNW of the succeeding switch NW, battery, earth. By means of the relay interrupter RU1, the rotary magnet DNW is operated until a free line in the P. B. X. group is found and thereupon the following circuit is completed: earth, contact 31pv, relay PNW, contact 32tnw, wiper c of succeeding switch NW on contact 2, night switch NS, contact 40 27b23, relay H31, wiper c of the preselector VW31, relay T31, battery, earth. Relay PNW operates in this circuit and at contact 30pnw opens the circuit for the rotary magnet DNW of the succeeding switch NW. Owing to the operation of relay PNW the circuit of relays PO and PV is maintained independently of contact 22g over contact 35pnw.

During the operation of the relay DNW relay UNW is energized and at contact 34unw maintains the circuit over wiper c of the final selector LW1 independently of the normal position of the succeeding switch NW. When the relay UNW releases on completion of the movement of the succeeding switch NW, the circuit over wiper c of the final selector LW1 is opened and relays P, G, An and BZ3 release. The marking of the line found free in the P. B. X. group has however been taken over by relay H31 which was energized over wiper c since relay H31 maintains the circuit over wiper c at contact 41h31 independently of contact 27b23. After the release of relay UNW on the operation of PNW the following circuit is completed for the rotary magnet DLW1; earth, contact 36po, wiper a of the allotter VO, contacts 60 31unw, 38pnw, 39tnw, 40u, 8p, rotary magnet DLW1, battery, earth. The rotary magnet advances the final selector LW1 one step and also operates contact 9d so that relay U is energized over: earth, off normal contact 2k, contacts 3v, 70 9d, winding II of relay U, battery, earth. Relay U opens the circuit of rotary magnet DLW1 at contact 40u and hence contact 9d restores to normal. After a short interval relay U releases and the circuit for the rotary magnet DLW1 is again completed over contact 40u and the final

selector LW1 is therefore advanced another step. The rotary magnet DLW1 and the relay U interact in this manner until the following circuit is completed over wiper c of the final selector LW1; earth, contacts 13c, 14v, 15u, windings I 5 and II of relay P, wiper c of the final selector LW1 in the overflow position 11, lead 16, wiper f of the succeeding switch NW in off normal position, contacts 33unw, 42fp, windings II of relay TNW, battery, earth. Relay P operates in this 10 circuit and by opening contact 8p prevents any further operation of the rotary magnet DLW1. Relay U is not again energized. Relay P closes contact 19p thus maintaining a circuit for itself independent of contacts 14v and 15u. Switching 15 through is again effected by relay P at contacts 20p and 21p. Relay TNW operates over wiper c of the final selector LW1 and by opening contact 32tnw and closing contact 43tnw interrupts the circuit for the relay PNW. There is now the 20 following circuit parallel to winding II of relay TNW over wiper c of the succeeding switch NW: earth, contacts 13c, 19p, winding II of relay P, wiper c of final selector LW1 in position 11, lead 16, wiper f of succeeding switch NW in off normal 25 position contacts 33unw, 43tnw, wiper c of succeeding switch NW in position 2, night switch NS, contact 41h31, relay H31, wiper c of switch VW31 in position 0, relay T31, battery, earth. Since a circuit now exists over winding II of relay 30 TNW and also over contact 43tnw and wiper c of the succeeding switch NW, seizure of the P. B. X. line SA31 over another succeeding switch is prevented since due to the earth through the low resistance winding of relay P which is now 35 connected to the line of the succeeding switch NW no test circuit can be completed for another succeeding switch. On the release of relay PNW the circuit for relays PV and PO is opened at contact 35pnw and the allotter VO is therefore released. 40

The calling subscriber has now been connected to the P. B. X. line SA31.

When the called subscriber replaces his receiver at the end of the conversation, the seizing relay C in the final selector LW is released in known manner and by opening contact 13c 45 interrupts the circuit for relays P, TNW, H31 and T31 whereupon these relays release. The rotary magnet DNW now receives impulses from the relay interrupter RU over: earth, contacts 44tnw, 45pnw, 46g, wiper e of succeeding switch NW in off normal position, rotary magnet DNW, battery, earth. The rotary magnet DNW now operates the succeeding switch NW until the succeeding switch NW has reached its normal position and hence the above traced circuit over wiper e of the succeeding switch NW is interrupted. 50

If a subscriber of the P. B. X. is wanted by a toll operator and all the P. B. X. lines accessible over the succeeding switch NW are busy, an existing local connection is broken down and the toll connection is set up in the following manner: The setting of the final selector LW1 and of the allotter VO takes place in the manner already 55 described. Since all the lines of the P. B. X. are busy including both the lines SA31 and SA32 shown in the drawings, no test circuit can be completed over relay PNW and wiper c of the succeeding switch NW. Accordingly the rotary 60 magnet DNW will advance the succeeding switch NW through positions 2, 3, and 4 and into position 5. In position 5 the following circuit is completed over relay PNW and FP: earth, contact 31pv, relay PNW, contact 32tnw, wiper c 65

of succeeding switch NW in position 5, contact 47b23, relay FP, battery, earth. Relays PNW and FP operate. By the opening of contacts 42/p and the closing of contact 48/p the high resistance winding of relay TNW is connected up. Moreover relay FP completes a locking circuit for the marking relay BZ3 over: earth, contact 49/p, winding II of relay BZ3, battery, earth. As already described the relay PNW brings the succeeding switch NW to rest by the opening of contact 30pnw. Relay UNW and P release and the final selector LW1 is set on to the overflow contact 11. When this contact is reached the following circuit is completed: earth, contacts 13c, 14v, 15u, windings I and II of relay P, wiper c of final selector LW1 in position 11, lead 16, wiper f of succeeding switch NW in off normal position, contact 33unw, windings I and II of relay TNW, battery, earth. Relay TNW operates in this circuit but not relay P. Since relay U is only energized for a short time and thus opens the circuit for relays P and TNW at contact 15u after a short interval, the following circuit is now completed for the relay TNW: earth, contact 49th, thermic relay TH, contacts 50tnw, 48/p, windings I and II of relay TNW, battery, earth. The toll operator is given a busy signal in any desired manner. She thereupon connects battery to the b-lead whereupon relay Y is energized. Relay Y closes contacts 51y and 52y so that a speaking connection is now completed between the calling toll operator and the P. B. X. subscriber SA32, since as the succeeding switch NW has been set on to contact 5 there is a connection over the multiple between 4 and 5 with the line SA32 connected to contact 4 of the succeeding switch. Relay TNW is held over: earth, contacts 13c, 18p, 57y, winding I and II of relay P, wiper c of final selector LW1, lead 16, wiper f of succeeding switch NW, contact 33unw, winding I and II of relay TNW, battery, earth.

When the subscriber reached over P. B. X. line SA32 releases his local connection, the blocking of the line reached over contact 4 is removed so that the following circuit is completed for relay WS: earth, contact 53tnw, relay WS, wiper d of succeeding switch NW in position 5, lead 54, contact 28b23, relay H32, wiper c of switch VW32 in position 0, relay T32, battery, earth. Relay H32 closes contact 55h32 so that the above circuit is maintained independently of contact 28b23. The succeeding switch receives an impulse from the relay interrupter RU over: earth, relay interrupter RU, contact 56ws, wiper e of succeeding switch NW in off normal position, rotary magnet DNW, battery, earth. The succeeding switch NW therefore advances to position 6 so that the following test circuit is now completed: earth, contacts 13c, 18p, 57y, windings I and II of relay P, wiper c of final selector LW1 in position 11, lead 16, wiper f of succeeding switch NW in off normal position, contacts 33unw, 43tnw, wiper c of succeeding switch NW in position 6, lead 58, contact 55h32, relay H32, wiper c of switch VW32, relay T32, battery, earth. Owing to the advance of the succeeding switch from position 5 to position 6 relay FP is released and at contact 49/p opens the holding circuit for relay BZ3. Owing to the completion of the test circuit over relay P, this relay effects switching through so that the toll connection has now been set up.

If all the P. B. X. lines are busy and a local subscriber wishes to set up a connection with a P. B. X. line the circuit operations just described

which are initiated by relay Y cannot take place since the subscriber has no means for operating relay Y in the final selector. Hence when the succeeding switch NW reaches position 5 owing to the group of P. B. X. lines being busy, relay FP operates but no test and holding circuit for relay TNW can be set up over relay P since this can only extend over contact 57y. As already described however, relay FP at contact 48/p completes the circuit for relay TNW and the thermic relay TH which becomes operative after a short interval, and by opening contact 49th opens the circuit for the relay TNW. The rotary magnet DNW is operated over contact 44tnw and hence the succeeding switch is restored to its normal position.

In order that during the night-time a calling subscriber shall only be connected with a particular line of the P. B. X. group, the operator before she leaves her position throws the night switch NS whereupon all the lines of the group except a single one, in the present case line SA32 are marked Engaged. The night call number is notified to the subscribers. If during the night-time the subscriber wishes to set up a connection over the group of P. B. X. lines with a trunk operator, he can only be connected to the particular line of the P. B. X. group and since this line is known to him he can give the trunk operator the number of the line used in order that she may call back.

If the group of P. B. X. lines, which in the present case comprises only lines SA31 and SA32, is for instance to be extended, i. e. an additional line is to be added, it is only necessary to connect this line to any free contact of the succeeding switch NW without in any way altering the operation of the final selector LW1 or making any changes in the multiple of this switch.

Having described the invention, what is considered to be new and is desired to be protected by Letters Patent will be set forth in the following claims.

What is claimed is:

1. In an automatic telephone system, an automatic switch, an auxiliary switch accessible to said automatic switch, a plurality of lines directly accessible to said auxiliary switch, means for operating said automatic switch to a position corresponding to one of the lines of said auxiliary switch, means responsive thereto for operating said auxiliary switch to select and connect with one of said lines, and means for reoperating said automatic switch to connect with said auxiliary switch.

2. In an automatic telephone system, an automatic switch, an auxiliary switch accessible to said automatic switch, a plurality of groups of lines directly accessible to said auxiliary switch, means for operating said automatic switch to a position corresponding to one of said groups of lines, means responsive thereto for operating said auxiliary switch to select and connect with an idle one of said selected group of lines, and means for then reoperating said automatic switch to connect with said selected line through said auxiliary switch.

3. In an automatic telephone system, a plurality of automatic switches having wipers, an auxiliary switch for each of said automatic switches and accessible thereto, wipers for each auxiliary switch, a plurality of groups of lines accessible to the wipers of each auxiliary switch, means for selecting an idle one of said automatic switches and operating it to a position in ac-

cordance with a particular group of lines, means responsive thereto for operating the auxiliary switch associated with the selected automatic switch to select an idle one of the lines in the 5 group selected, means for again operating said automatic switch to connect its wipers with the wipers of its operated auxiliary switch and extend the connection through said automatic and auxiliary switches to said selected line.

10 4. In an automatic telephone system, a plurality of automatic switches, an auxiliary switch individual to and accessible to each automatic switch, wipers for said auxiliary switch, groups of lines accessible to the wipers of each auxiliary 15 switch, a marking line for each group of lines accessible to said automatic switch, means for operating one of said automatic switches to connect with a marking line of a particular group of lines, a call allotter common to said automatic 20 switches for controlling the auxiliary switch of the operated automatic switch to select and connect with an idle one of said selected group of lines over its wipers and for reoperating said automatic switch from its position on said marking 25 line to connect with the wipers of its auxiliary switch and complete the connection through said wipers to the selected line.

5. In an automatic telephone system, automatic switches, an auxiliary switch associated with each 30 automatic switch having wipers, a plurality of

groups of lines accessible to said auxiliary switch through its wipers, marking lines each corresponding to a particular group of lines accessible to said automatic switches, said auxiliary switch connected to bank contacts located in a position 5 following the marking line contacts in the bank of said automatic switch, means for operating an automatic switch to a position to connect with one of said marking lines, and an allotter switch common to said automatic switches operated to 10 control said auxiliary switch to select an idle one of the lines of the marked group to connect its wipers thereto and for then operating said automatic switch to a position to connect with the selected idle line through the wipers of its auxiliary switch. 15

6. In an automatic telephone system, an automatic switch having wipers, an auxiliary switch accessible to said automatic switch through its wipers, a plurality of groups of lines accessible 20 to said auxiliary switch, means for operating said automatic switch for a local connection to mark a particular group of said lines, means for operating said auxiliary switch to select one of an idle line of the selected group and extend a connection thereto, and means for reoperating said auxiliary switch for a toll connection in case all 25 of said lines are busy to operate said auxiliary switch to extend a connection to said busy line.

FRITZ LUBBERGER. 30
